GEORGE B. COCKER, OF GASTONIA, NORTH CAROLINA, ASSIGNOR TO COCKER MACHINE AND FOUNDRY COMPANY, OF GASTONIA, NORTH CAROLINA, A CORPORATION OF NORTH CAROLINA

APPARATUS TO PREPARE YARNS FOR WEAVING

Application filed January 27, 1928. Serial No. 249,790.

This invention is concerned with the preparation of yarns for weaving, and more specifically with sizing, slashing and warping of fine yarns; e. g., single ply cotton 5 strands, to render them sufficiently strong for capacity to resist rupture under strains induced incidental to subsequent manipulation in the looms by which they are incorporated into textile fabrics. The usual 10 method heretofore practiced in accomplishing the foregoing involved two distinct and separate steps, to wit: section beaming of yarn ends, and mounting of the section beams in a creel associated with a "slasher" 15 for grouping, sizing, and final winding of the yarn ends on warp beams suitable for direct transfer to the looms; the number of section beams required for the purpose depending of course upon the sum total of the 20 ends desired on the final warp beam. Even with exercise of the utmost care in winding, it is absolutely impractical to produce section beams with the yarns packed to the same density in each due to diverse influences, such as variation in the gage of the 25 yarns, differences in tension, changes in atmospheric conditions, etc. Therefore, subsequent application of rotative restraint to the same degree upon all the section beams employed in the creel associated with the slasher did not predetermine uniform tension on the yarns during the slashing process, with the result that this operation was invariably attended by frequent ruptures resultant upon stretching of the yarns 30 beyond their tensile strength. Moreover, upon exhaust of the section beams, it was necessary to completely stop the apparatus for substitution of other beams and re- 35 threading it with the new ends, a procedure that was not only tedious and exacting but entailed wasting of comparatively large amounts of yarn.

My invention is directed toward providing an efficient reliable apparatus whereby 40 the operation of yarn preparation is made absolutely continuous with delivery of the ends under minimum tension. This desideratum I attain through employment of 45 a magazine creel (one in which the yarns

are drawn over end from stationary individual packages grouped for successive substitution) to the advantages of completely eliminating the initial section beaming step hereinbefore referred to, eliminating all 55 waste, and attaining increased speed and higher productive output from the apparatus.

Other objects and advantages will be apparent from the detailed description following of the drawings; whereof, Fig. I shows more or less diagrammatically, the side elevation of a yarn preparing apparatus conveniently embodying my invention.

Fig. II is a plan view of the organization. 60

Fig. III shows in plan a fragment of the yarn package creel, of the magazine type, which I employ as a part of the apparatus.

Fig. IV is a fragmentary rear elevation of one of the yarn guide boards employed 70 in connection with the creel.

Fig. V is a sectional view to a larger scale taken locally, as indicated by the arrows V—V in Fig. IV.

Fig. VI shows a vertical section of the reserve accumulator which I interpose between the creel and the slasher; and 75

Fig. VII is a conventional diagram of the various devices that cooperate in effecting automatic partial, or total, stoppage of the 80 apparatus consequent upon yarn breakage.

With reference first more particularly to Figs. I and II, it will be observed that the apparatus comprises a creel 10 wherewith is associated an expansion comb frame 11, a slasher 12 with its sizing vat 13, and an accumulator 14 which is located in the interval between said expansion comb frame and the sizing vat. 85

In the present instance the creel 10 embodies a number of separate upright wing sections 15 stationarily supporting a multiplicity of yarn packages having the form of cones 16, said sections 15 being disposed in opposing couples and in equal numbers to opposite sides of the longitudinal center line of the apparatus with capacity for angular adjustment to suit various conditions of practice. As shown in Figs. I and III, the cones 16 are arranged in vertically- 90

spaced horizontal rows and grouped in pairs, the components of each pair being complementarily tilted to axially align with a common guide 17, so that, by tying the leading end of yarn Y on the auxiliary cone to the trailing end on the active cone of a pair, a continuous supply may be had from the creel 10 by successive substitutions, as the packages or cones 16 are exhausted. A yarn package support of the described type is known in the art as a "magazine creel", and although not in itself novel to my invention, its use is, however, favorable in the present connection, since, aside from affording a source of continuous yarn supply, it is capable of delivering at very much higher speeds than other types of creels, wherein tensional strain is imposed on the yarns Y by virtue of their having to rotate the packages 16. With each of the creel sections 15, I associate a transverse guide board 18 constructed from insulating material with eyes 19 serially arranged in horizontal lines at levels corresponding to the horizontal rows of the yarn cones 16. At the back, and beneath each row of the eyes 19, the guide board 18 is equipped with a series of electric stop control instrumentalities 20 to an equal number. These control instrumentalities 20 are bent to the angular configuration shown, preferably from stout wire, while the components of each group are mounted for free and independent swinging movement upon a common fulcrum rod 21. Normally, the loop ends of the controls 20 are supported by the yarns Y in the interval between the eyes 19 and a directional guide bar 22. In the event of a break occurring in a yarn Y, the corresponding control 20 is released to drop to the dotted line position shown in Fig. V, thereby to electrically bridge between the metallic bearing bracket plate 23, supporting the fulcrum rod 21, and a parallel companion contact plate 24. The plates 23, 24 of the several groups of controls 20 are respectively connected in parallel by conductor strips 25, 26 (see Fig. IV) leading to terminal posts 27, 28. The function of the electric control system just described will be set forth in detail later on herein.

After passing through the guide boards 18, the yarn ends Y are directed to the frame 11, which, at opposite ends, supports expansion combs 31, 32, of a conventional type, to reduce the warp sheet to the desired width for progression and winding in other parts of the apparatus. The expansion comb frame 11 also provides bearings for a pair of superposed draft rolls 33, 34 which are instrumental in drawing the yarns Y from the creel 10 and through the expansion combs 31, 32. These draft rolls 33, 34 are driven, through interposed reduction gearing 35, from a shaft 36 equipped with

tight and loose pulleys 37, 38 between which a drive belt 39 is transferable by a shipper 40 fast on a slide rod 41.

The warp sheet having now been contracted to a definite width, is next passed to the accumulator indicated at 14 in Figs. I and II, and shown in greater detail in Fig. VI. In this accumulator 14 the yarns Y are fastened for maintenance of a reserve through cooperation of positionally-fixed upper rollers 45 and floating lower rollers 46 that are free to rise and fall under guidance of slots 47 in opposite sides of the accumulator frame. For the purpose of insuring parallel travel, relative to the fixed upper rollers 45, the floating rollers 46 are provided with pinions 48 for cooperation with toothed racks 49 along the guide slots 47. An electric stop control 50, shown near the top of the accumulator frame, comprises a vertically shiftable member 51 with oppositely-projecting arms extending horizontally across the path of the floating rolls 46. Thus, when the member 51 is lifted through rise of either (or both) of the floating rollers 46, a spring contact 52 thereon will bridge a pair of conductor terminals 53, 54 set in an insulatory block 55 on the accumulator frame. The specific function of the stop control 50 will also be explained in detail hereinafter.

The vat 13, associated with the slasher 12, is of usual construction having guide rollers 60 to direct the yarns Y into the size bath, and squeeze rolls 61 to subsequently remove the excess. The same is true of the slasher 12, which, as shown, embodies internally heated rotating drums 62, 63 whereabout the yarns Y are successively passed for drying immediately upon emerging from the size bath 13. The aforesaid drums 62, 63, and the size vat 13 may be heated from a common source of steam through connecting piping, shown at 64 in Fig. I. After drying, the yarns Y are finally directed over various guide and feed rollers 65, on the slasher frame 66, to the rotating warp beams 67. In the present instance, the main shaft 68 of the slasher 12 is equipped with a high speed pulley 69, a low speed pulley 70, and an idler pulley 71, as well as with a sliding shipper 72 for transferring the drive belt 73 from one to the other of said pulleys.

In the drive system for the apparatus I interpose a conventional type of manually-controllable variable speed device 75, which may derive motion from a suitable prime mover, for example, an electric motor 76, (Figs. I and II). The power from the shaft 77 of the variable speed device 75 is transmitted, through a belt 78 and countershaft 79, to the driving belt 73 of the slasher 12; while the movement of the differential speed shaft 80 of said device is, at the same time, communicated to the belt 39 by which the

yarn draft rollers 33, 34, on the expansion comb frame 11, are driven.

The means for automatically controlling the apparatus in the event of yarn rupture includes a longitudinal rod 85 which is supported for endwise sliding in opposition to the pull of a spring 86, by bearings shown at 87 in Figs. II and VII. At the right hand end, the rod 85 has an extension 88 that is attached, with capacity for lost motion, by a friction coupling 89, the free end of said extension having pivotal connection with an arm 90 secured on the vertical shaft 91 which, at the top, has a second arm 92 adapted to communicate imparted movement to the belt shipper slide rod 41 associated with the drive of the draft rollers 33, 34. Near its left hand end the rod 85 has an operative connection, through a bell crank lever 93, with the belt shipper 72 of the slasher drive. Intermediate its ends, the rod 85 is equipped with lugs 94, 95 which are appropriately spaced for successive cooperation, respectively, with electrically-actuable stops 96, 97 of standard design embodying, for example and as graphically depicted in Fig. VII, latch bolts 98 with solenoids 99 for retracting them against gravity or spring pressure from a normal projected position. As shown in Fig. VII, the solenoid coils 99 of the latch means 96, 97 are connected by leads 100 and through the contact controls 20 and 50, respectively on the creel 10 and the accumulator 14, in parallel with line conductors 101, 102, extending to a convenient source (not shown) of electric current. The wiring system further includes switches 104, 105 (preferably of the push button type) whereby the controls 20 and 50 may be bridged or shunted to enable stoppage of the apparatus under manual control.

The operation of the apparatus is as follows: With the variable speed device 75 properly adjusted and the draft rollers 33, 34 running in synchronism with the slasher 12, the yarn ends Y will be continuously drawn from the creel 10, passed through the expansion combs 31, 32 on the frame 11 under draft of the rollers aforesaid, pro-

gressed through the accumulator 14 and bath 13, thence around the drying drums 62, 63 of the slasher 12, and finally wound upon the warp beams 67. In the event of yarn breakage at the creel 10, the corresponding stop control 20 (or controls) will drop as previously explained hereby closing the circuit through latch means 96. With resultant tripping of the latch means 96, the slide rod 85 will under recoil of the spring 86 shift to the left (Figs. II and VII) until the lug 95 thereon engages the bolt 98 of latch means 97. This shog of the slide rod 85 is attended by shifting of the belt shipper 40, associated and the draft rolls 33, 34, 65 from the tight pulley 37 to the loose pulley

38 with consequent suspension in the draft of yarn ends Y from the creel 10; and concurrently cause shifting of the belt shipper 72 associated with the slasher 12 from the high speed pulley 69 to the low speed pulley 70. Thereupon the slasher 12 will operate at reduced speed; and through temporary satisfaction of the latter from the reserve in the accumulator 14, a time interval is afforded for repairing any minor breaks. When the break or breaks in the yarn Y have been remedied, the apparatus may be re-started by manually shifting the slide rod 85 with the aid of either of the hand levers 106 shown in Fig. VII whereupon the operation proceeds continuously as before. However, in the event that the reserve in the accumulator 14 is exhausted before the broken yarn ends Y can be repaired, the slasher 12 is automatically brought to a complete standstill 85 through rise of either or both of the floating rolls 46 to a level sufficiently high to actuate the stop control 50 and cause closure of the circuit through the latch means 97. Consequent upon withdrawal of the bolt 98 of the latch means 97, the slide rod 85 is released a second time for further travel, the belt 39 associated with the draft rollers 33, 34 remaining on the loose pulley 38 (by virtue of provision for lost motion in the friction 95 coupling 89), while the belt shipper 72 associated with the slasher 12 is advanced to transfer the belt 73 to the loose pulley 71.

By use of the specific type of creel 10 herein shown and described, it will be seen that the yarns Y are delivered absolutely free from restraint so that the apparatus can be run at very high speeds. It is, however, obvious that any other form of individual package creel may be substituted, and likewise, any other form of standard slasher 12 employed in lieu of the type illustrated, these considerations being entirely optional and having no influence upon the general performance of the apparatus in attainment of the advantages referred to in the introductory portion of this specification.

Having thus described my invention, I claim:

1. In apparatus to prepare yarns for weaving, a magazine creel capable of continuously supplying yarn ends from individual packages at minimum uniform tension and at high speeds; in combination with means for continuously drawing said yard ends from the creel, a slasher, automatic means to concurrently stop draft of the yarn ends from the creel and to reduce the speed of the slasher in the event of yarn breakage, and means for maintaining a reserve accumulation in the yarns to temporarily satisfy the demands of the slasher at the reduced speed in affording a time interval for repair of the yarn breaks.

2. In apparatus to prepare yarns for

weaving, a magazine creel capable of continuously supplying yarn ends from individual packages at minimum uniform tension and at high speeds; in combination with
5 means for continuously drawing said yarn ends from the creel, a slasher, automatic means to concurrently stop draft of the yarn ends from the creel and to reduce the speed of the slasher in the event of yarn breakage,
10 means for maintaining a reserve accumulation in the yarns to temporarily satisfy the demands of the slasher at the reduced speed in affording a time interval for repair of the yarn breaks, and coordinated automatic
15 means to stop the slasher upon exhaustion of the reserve accumulation aforesaid.

3. In apparatus to prepare yarns for weaving, a magazine creel capable of continuously supplying yarn ends from individual packages at minimum uniform tension and at high speeds; in combination with means for continuously drawing said yarn ends from the creel, a slasher, an accumulator between the draft means and the slasher comprising
20 positionally fixed and movable rollers cooperating to maintain a festooned reserve in the yarns, automatic means to concurrently stop draft of the yarn ends from the creel and to reduce the speed of the slasher in the
25 event of yarn breakage with temporary satisfaction of the slasher from the reserve in the accumulator, and means operative upon approach of the movable rollers of the accumulator to the companion fixed rollers to
30 automatically stop the slasher also when the reserve in the accumulator is exhausted.

4. In apparatus to prepare yarns for weaving, a magazine creel capable of continuously supplying yarn ends from individual packages at minimum uniform tension and at high speeds; in combination with means for continuously drawing said yarn ends from the creel, a slasher, an accumulator between the draft means and the slasher, means to
40 normally synchronize the speed of the draft means and the slasher for maintenance of reserve yarn in the accumulator, and automatic means to concurrently stop draft of the yarn ends from the creel and to reduce the speed of the slasher in the event of yarn
45 breakage with temporary satisfaction of the slasher from the reserve maintained in the accumulator.

In testimony whereof, I have hereunto
55 signed my name at Philadelphia, Pennsylvania, this 24th day of January, 1928.

GEORGE B. COCKER.
